COMBINED INDUCTOR AND WORK-SUPPORTING MEANS

Rudolph M. Serota, Milwaukee, Wis., assignor to
Allis-Chalmers Manufacturing Company, Milwaukee, Wis., a corporation of Delaware

Application February 5, 1949, Serial No. 74,784

4 Claims. (Cl. 219—47)

1

This invention relates in general to improvements in means for inductively heating a workpiece, and in particular to improved means for heating and for releasably holding a workpiece.

A principal object of the present invention is to provide an improved heating inductor in which the workpiece to be heated is releasably supported within and by the inductor.

Another object of the invention is to provide an improved heating inductor which can be divided and in which the workpiece to be heated is releasably supported within the inductor.

Another object of the invention is to provide an improved heating inductor which can be divided and in which a workpiece to be heated is releasably supported within the inductor by a divisible portion of the inductor.

Another object of the invention is to provide an improved heating inductor which can be divided and in which a workpiece held by the inductor for heating is released upon dividing the inductor.

Other objects will appear as the description proceeds.

The novel features of the invention and how the objects are obtained will be apparent from this specification and the accompanying drawings showing several embodiments of the invention and forming part of this specification and all the novel features are intended to be pointed out in the appended claims.

In the drawings:

Fig. 1 is a plan view of an induction device, or oven, as it will hereinafter be referred to, embodying the invention;

Fig. 2 is a side elevation of the induction oven shown in Fig. 1, a portion of the side wall and part of the electrical contacts thereof being broken away to reveal the divided structure of the heating inductor;

Fig. 3 is a front elevation of the induction oven of Fig. 1, a portion of the reinforcing structure thereof being broken away to reveal a cooling duct for the inductor;

Fig. 4 is a side elevation of an alternative embodiment of the induction oven shown in Fig. 1; and

Fig. 5 is a section taken on the line V—V in Fig. 1 showing the contact means for completing the electrical circuit through the inductor.

The invention illustrated in Figs. 1 to 5 can be embodied in many types of induction ovens having divisible inductors of various shapes, but for purposes of exemplification, the invention has been embodied in an induction oven having

2

a divisible, single-turn, parallelepipedous-shape inductor.

Referring to Figs. 1 and 2 in which similar parts are identified by the same reference characters, the oven here shown for inductively heating a workpiece is constructed in the following manner.

A plate 10 of insulating material having a centrally disposed opening 11 therein provides a base for a pair of upward-extending, parallelly-disposed, spaced side walls 12, also of insulating material. The side walls 12 are joined at their forward ends by a transversely-disposed, reinforcing bar 13 of insulating material, and at their rearward ends by a transverse wall 14 likewise of insulating material, the connection between the walls being made by means of screws 15.

The base 10 and walls 12, 14 together form an oven box within which a divisible, parallelepipedous or box-type inductor 17 is so positioned that the inductor winding is sunk below the side walls 12, leaving only the reinforcing structure, cooling structure, and current leads, hereinafter described, extending above.

20 The inductor 17, as hereinbefore mentioned, is preferably shaped like a parallelepiped—one having the front and rear faces open—and is wound using a ribbon conductor of comparative thinness and large transverse width. As best shown in Figs. 1 and 2, the inductor 17 comprises essentially a first or fixed portion, and a second or movable portion, described as follows.

25 The fixed portion of the inductor 17 comprises first and second bilaterally-symmetrical, conductor elements 18, having respective coplanar segments 19 defining the top of a parallelepiped, and respective depending side segments 20 defining the sides of the parallelepiped. In order to lend rigidity to the fixed portion of the inductor 17, the coplanar segments 19 are provided 30 respectively with a plurality of reinforcing ribs 21 extending along the outside surface of the segments 19 in the direction of the inductor turn, i. e., parallel to the transverse rear wall 14.

35 The depending side segments 20 extend in coparallel relation respectively adjacent to but spaced from the side walls 12, the spacing being effected by spacer pads 23 respectively inserted between the segments 20 and the side walls 12. The conductor elements 18 are supported in fixed 40 position relative to the oven box by a plurality of bolts 24 which pierce the side walls 12 and spacer pads 23 to thread into the conductor segments 20.

45 The movable portion of the inductor comprises a third conductor element, or, as it will herein-

after be referred to, a dump gate 25, engageable with the side segments 20 of the first and second conductor elements 18, the dump gate 25 being pivotally connected to the side walls of the oven box by hinge pins 26 and swingable vertically about a transverse axis through the pins 26. In order to provide additional bearing surface for the hinge pins 26 and also to prevent wear of the side walls 12, apertured bosses 27 are respectively positioned adjacent the outside surface 10 of the side walls 12.

The dump gate 25 has a planar conductive segment 28 defining the bottom of the parallelepiped and extending parallel to the coplanar segments 19 of the first and second conductor elements 18. 15 The planar segment 28 has the dual function of passing current through the dump gate 25 and providing a support for sustaining workpieces, not shown, within the inductor 17. In order to impart structural rigidity to the dump gate 25 and reinforce the planar segment 28 in its supporting function, a plurality of reinforcing ribs 29 are provided extending transversely of the oven box along the underside of the planar segment 28.

The reinforcing ribs 29 lie between and at right angles to a pair of side supporting arms 31 extending along either side of the dump gate 25 parallel to the side walls 12. The arms 31 are respectively provided with upward-extending ears 32 and downward-extending ears 33. The upward-extending ears 32 are pierced to respectively receive in nonrotatable engagement the hinge pins 26. The downward-extending ears 33 are likewise pierced to respectively receive bolts 35 for securing an operating handle 36 in fixed position between the ears 33. The handle 36 provides the means by which an operator can grasp the dump gate 25 to swing it vertically about the hinge pins 26.

Supported on the planar segment 28 of the dump gate 25 is a flat tray 38 adapted to be slid into and out of the inductor 17 when the dump gate 25 is in the position shown in solid lines in Fig. 2. The tray 38 is made of insulating material and provides the direct supporting surface upon which workpieces, not shown, may be deposited for heating by the inductor 17. The tray 38 has a handle 39 which extends outward from the oven box and also has a pair of parallelly extending guides 40 secured to its upper surface, the function of the guides 40 being to forestall any movement of the workpieces toward the side segments 20 of the inductor 17. The tray 38 is prevented from sliding out of the inductor 17, when the dump gate 25 is in the position shown in broken line in Fig. 2, by retaining fingers 41 which are secured to the tray 38 and engage the foremost reinforcing rib 29 of the dump gate 25.

Means for retaining the dump gate 25 in mechanical engagement with the fixed portion 18 of the inductor 17 when the dump gate 25 is swung upward to the position shown in solid lines in Fig. 2 comprises releasable retaining means 42 mounted on pad 43 on the rear wall 14 of the oven box. The releasable retaining means 42 comprises a spring-biased bolt 45 adapted to slide in an opening in the rear wall 14 to engage the underside of the dump gate 25. The bolt 45 is provided at its rearward end with a pin 46 which is engaged by one end of a pivoted bell crank 47. The other end of the bell crank 47 is pinned to a link 48 having a pinned connection with the armature plunger 49 of a vertically disposed solenoid 50. Upon energization of the solenoid 50

5 by means not shown, the bolt 45 is retracted allowing the dump gate 25 to swing downward under the influence of gravity and the force exerted by bias springs 52 respectively surrounding the hinge pins 26.

Means for effecting an electrical connection between the dump gate 25 and the fixed portion 18 of the inductor 17 comprises, as shown in Figs. 2 and 5, longitudinally-disposed bar contacts 53 secured respectively to either side of the dump gate 25 as by brazing, and wiping contact finger assemblies 54 bolted respectively to conductive pads 54' mounted on the side segments 20, the contacts 53 and wiping finger assemblies 54 forming a releasable electrical connection.

The inductor 17 is energized through first and second bus bars 55 connected to the fixed portion 18 of the inductor 17, the first bus bar 55 being secured to the coplanar segment 19 of the first conductor element 18, and the second bus bar 55 being secured to the coplanar segment 19 of the second conductor element 18, the respective connections being effected by brazing or the like.

A source of alternating current—the source 25 being of any suitable type and conventionally represented in the drawing of Fig. 2 as a synchronous generator 56—provides the means for energizing the inductor 17. The generator 56 is connected to the inductor 17 through the bus bars 55 and the energization of the generator is controlled by a circuit breaker 57 in the field circuit 58 of the generator 56. Control of the field circuit breaker 57 is effected by means of an auxiliary circuit which includes a second circuit breaker 59 and an interlocking means 60 mounted on one of the side walls 12 of the oven box below the hinge boss 27.

The interlocking means 60 comprises a pair of contacts 61 that are normally open when the dump gate 25 is tilted to the position shown in broken line in Fig. 2. When the gate 25 is swung upward to the position shown in solid line in Fig. 2, in which position the gate 25 is electrically connected to the fixed portion 18 of the inductor 17, a projection 62 on the depending ear 33 of one of the side arms 31 engages a button 63 on the interlocking means 60 and closes the contacts 61. Closure of contacts 61 permits the auxiliary circuit to be manually closed, as by manually closing 45 in the second circuit breaker 59, which breaker then assumes exclusive control of the auxiliary circuit as long as the gate 25 is engaged. When the circuit breaker 59 is closed, a holding-in coil 59' takes over—the tripping switch 51 thereof having been previously closed—and retains the breaker in closed position as long as the auxiliary circuit remains energized through the interlocking means 60. The purpose of the interlocking means 60 is to permit energization of the generator 56 after conductive engagement of the dump gate 25 with the fixed portion 18 of the inductor 17, and to prevent energization of the generator 56 and the inductor 17 when the gate 25 is tripped to assume the position shown in broken line in Fig. 2.

Cooling means for increasing the current conducting capacity of the inductor 17 comprises cooling ducts 65 respectively positioned within the bus bars 55, which ducts connect with cooling conduit laid over and across the fixed and movable portions of the inductor 17, the conduit being fastened to the inductor portions by brazing or the like. Flexible hose connections 66 respectively join the conduit 67 of the fixed portion 18

of the inductor 17 to the conduit 68 of the dump gate 25.

The flow of cooling fluid through the cooling means of the inductor 17 may be traced as follows. Cooling fluid from a source, not shown, may be introduced through a first connecting nipple 69 to the duct 65 in the first bus bar 55, from where it flows to the conduit 67 in the first conductor element 18. From the first conductor element 18, fluid is conveyed by one of the flexible hoses 66 to the conduit 68 in the dump gate 25. The fluid circulates around the dump gate 25 and then is returned by a second flexible hose 66 to the conduit 67 in the second conductor element 18, from which the fluid flows through the duct 65 in the second bus bar 55 and out a second connecting nipple 69. It will be apparent upon referring to Fig. 1 that the conduit 67, 68 is so connected and arranged with respect to the inductor portions as to provide for effective cooling of the inductor 17 during periods of energization.

Having described the structure of the induction oven incorporating one embodiment of the invention, it is now meet to describe the operation of the oven and how a workpiece to be heated is releasably held therein.

The oven may be charged by removing the tray 38, wholly or partially, and placing one or more workpieces on the tray 38, then sliding the tray 38 back in the oven; or, the oven may be charged by simply inserting the workpieces within the inductor 17 so as to have them rest upon the tray 38. The tray 38 and dump gate 25 will occupy at the time of charging the position shown in solid line in Fig. 2. After the oven is charged the inductor 17 is energized from the source of high frequency current 56, and the inserted workpieces heated by induction. If it is desired to heat only one side of a workpiece the insulated tray 38 may be dispensed with and the workpiece may be placed directly on the surface of the planar segment 28 of the dump gate 25. Upon energization of the inductor 17 by manually closing the circuit breaker 59, the side of the workpiece that is touching the conductive segment 28 of the gate 25 will remain cool while the opposite side of the workpiece will become hot under the action of the induced currents.

Following the heating of the workpieces, the inductor 17 is deenergized by opening the switch 51 to trip the breaker 59 and cause deenergization of the generator 56. The dump gate 25 is then tripped by energizing the solenoid 50, the plunger 49 moving upward and retracting the bolt 45 to release the gate 25. Upon release, the gate 25 swings vertically downward about the hinge pins 26 under the influence of gravity and the force exerted by the biasing springs 52. The tripping of the gate 25 opens the contacts 61, preventing the auxiliary circuit from being closed through the breaker 59, thereby preventing energization of the generator 56.

Although the biasing springs 52 may not be necessary with all embodiments of the invention it has been found that the electrical contacts 53, 54 may exert a frictional resistance greater than the gravitational attraction on the dump gate. When this condition exists biasing springs such as the springs 52 shown in Fig. 1 are necessary if manual manipulation of the dump gate 25 to the releasing position is to be avoided.

After being tripped, the dump gate 25 moves to the position shown in broken line in Fig. 2, releasing the workpieces from the inductor, and allowing them to slide from the tray 38 through

the opening 11 in the base plate 10. The dump gate 25 is then manually returned to a recharging position by having the operator grasp the handle 36 and exert a downward pull. During this procedure the releasable bolt 45 is cammed inward by the end of the gate as it swings by and the bolt 45 is then returned to a position under the gate 25 by the action of a biasing spring 71 to retain the gate 25 in the engaged position for a recharging operation.

Referring now to Fig. 4, an alternative embodiment is shown in which the tray is wholly supported by the oven box when the tray is within the closed inductor, as contrasted with the embodiment shown in Fig. 2 in which the tray is supported by a movable portion of the inductor. In the alternative embodiment of Fig. 4, in which parts similar to like parts in the first described embodiment are designated by the same reference numerals, a base plate 10 similar to the base plate 10 of Fig. 2 supports a pair of side walls 12 and a transverse rear wall 14. The oven box formed by the three walls 12, 14 is similar to the oven box of the first embodiment. An inductor 17 having a fixed portion 18 similar to the fixed portion shown in Fig. 1 is sunk within the oven box and retained therein in a similar manner.

The movable portion of the inductor is pivotally connected to the side walls by hinge pins 26, only one of which is indicated in Fig. 4, and is swingable in a vertical direction similar to the movement of the dump gate 25 in the first embodiment, the movable portion herein comprising a rectangular-shape dump gate 72 having a planar conductor element 28 on the upper side thereof. Electrical connecting means 53, 54 similar to the electrical contacts hereinbefore described in connection with the embodiment of Fig. 5, are fastened to the fixed portion 18 of the inductor and to the dump gate 72 for carrying current between the fixed and movable portions upon engagement of the two.

A workpiece-supporting tray 73 extending parallel to and above the dump gate 72 is pivotally connected to the side walls by hinge pins 74, only one of which is shown in Fig. 4. A pivoted link 75 joins the tray 73 and the dump gate 72 and provides for a parallel motion of the tray 73 and gate 72 upon movement thereof. Releasable means 77 for sustaining the gate 72 and tray 73 in charging and operating position, as shown in Fig. 4, is mounted on a pad 78 on the rear wall. The releasable means 77 comprises spring-biased bolts 79 adapted to slide in openings in the rear wall 14 for engagement respectively with the tray 73 and dump gate 72. The bolts 79 are fastened together for simultaneous movement by means of a slidably yoke 80 connected to a bell crank 47. The bell crank 47 is in turn connected to the plunger 49 of a vertically disposed solenoid 50 in the same manner as hereinbefore described in connection with the embodiment of Fig. 2. Energization of the solenoid 50 causes retraction of the bolts 79 allowing the gate 72 and tray 73 to simultaneously swing downward, dumping any workpiece which may be on the tray 73 through the opening 11 in the base plate 10.

The tray 73 may have a second tray 81, the counterpart of the removable tray 38 of the first embodiment, which tray 81 is similarly held in position, when the tray 73 tips, by means of a plurality of lugs 82 engaging with the tray 73, only one of the lugs 82 being shown in Fig. 4. Thus the charging of the oven of the alternative

embodiment may be effected in a manner similar to that recounted for the first embodiment.

Although but two embodiments of the present invention have been herein illustrated and described, and although these embodiments have been described particularly in connection with single-turn, box-type or parallelepipedous-shape inductors, it will be apparent to one skilled in the art that the invention may have desirable functional utility in other types or shapes of inductors. And it should be understood that the invention of the appended claims is not limited to the exact details of design and construction described herein, for obvious changes and modifications within the scope of the claims will be apparent to those skilled in the art.

It is claimed and desired to secure by Letters Patent:

1. A current-carrying coil for inductively heating a workpiece, comprising first and second planar conductors having relatively parallel side portions depending therefrom, a third planar conductor having a plurality of contact surfaces, said third conductor being movable toward and away from said first and second conductors, means for effecting engagement of said third conductor with said first and second conductors upon movement of said third conductor toward said first and second conductors including a plurality of depending contact fingers connected to each of said portions for electric engagement with said contact surfaces upon movement of said third conductor toward said first and second conductors and including means for retaining said third conductor in engagement with said first and second conductors, insulator means carried by said third conductor for releasably supporting said workpiece in heating position within said coil, and releasable means for effecting withdrawal of said third conductor from engagement with said first and second conductors to release and drop said workpiece from said coil.

2. A current-carrying coil for inductively heating a workpiece, comprising first and second planar conductors having relatively parallel side portions depending therefrom, a third planar conductor having a plurality of contact surfaces, said third conductor being movable toward and away from said first and second conductors, means for effecting engagement of said third conductor with said first and second conductors upon movement of said third conductor toward said first and second conductors including a plurality of depending contact fingers connected to each of said portions for electric engagement with said contact surfaces upon movement of said third conductor toward said first and second conductors and including releasable means for retaining said third conductor in engagement with said first and second conductors, means carried by said third conductor for releasably supporting said workpiece in heating position within said coil, and releasable means for effecting

withdrawal of said third conductor from engagement with said first and second conductors to release and drop said workpiece from said coil.

3. In an induction oven for heating a workpiece the combination of a pair of insulated side walls enclosing at least a portion of a parallelepipedous-shaped inductor, said inductor comprising mutually engageable first and second portions, said second portion comprising a structure hingedly supported on said side walls for swingable movement and biased to a disengaged position relative to said first portion, means associated with said second portion for supporting the work-piece above said second portion in insulated relation therewith, a plurality of relatively engageable electric contacts associated with said first and second portions for electrically connecting said portions upon mutual engagement thereof, means for retaining said second portion in engagement with said first portion when said second portion is swung from said disengaged position into an engaged position with said first portion, and releasable means for effecting movement of said second portion from said engaged position to said disengaged position to release and drop said workpiece from said oven.

4. In an induction oven for heating a workpiece the combination of a pair of insulated side walls enclosing at least a portion of a parallelepipedous-shaped inductor, said inductor comprising mutually engageable first and second portions, said second portion comprising a structure hingedly supported on said side walls for swingable movement and biased to a disengaged position relative to said first portion, means associated with said second portion for supporting the work-piece above said second portion, a plurality of relatively engageable electric contacts associated with said first and second portions for electrically connecting said portions upon mutual engagement thereof, means for retaining said second portion in engagement with said first portion when said second portion is swung from said disengaged position into an engaged position with said first portion, and releasable means for effecting movement of said second portion from said engaged position to said disengaged position to release and drop said workpiece from said oven.
